UNITED STATES PATENT OFFICE.

JASON BAKER, OF BATTLE CREEK, IOWA.

INSULATOR-PIN.

1,176,333.

Specification of Letters Patent.

Patented Mar. 21, 1916.

Application filed June 28, 1913. Serial No. 776,337.

To all whom it may concern:

Be it known that I, JASON BAKER, a citizen of the United States, residing at Battle Creek, in the county of Ida and State of Iowa, have invented certain new and useful Improvements in Insulator-Pins, of which the following is a specification.

This invention relates to insulator pins and more particularly to that type of insulator pin which is used in connection with cross arms for the stringing of various types of electrical wires such as telegraph, telephone, or the like and has for its primary object the provision of an improved insulator pin which will eliminate many of the objections and defects existing in the type of insulator pin now employed and will provide a simple, inexpensive and practical device of this nature.

Another object of this invention is the provision of an insulating pin which may be stamped from a single piece of sheet metal and formed so as to efficiently grip a cross arm or the like and support the insulator in an efficient manner without in any manner detracting from the strength of the cross arm or aiding in the decaying of the same as is commonly the case with the ordinary wood or metallic pins which are inserted through the cross bars.

With the foregoing and other objects in view, this invention consists in such novel features of construction, combination and arrangement of parts as will be hereinafter more fully described, illustrated in the accompanying drawings, and claimed.

In describing the invention in detail, reference will be had to the accompanying drawings wherein like characters of reference designate like or corresponding parts throughout the several views, and in which,

Figure 1 is a side elevation of the improved insulating pin; Fig. 2 is a vertical section through the insulating pin; Fig. 3 is an end view of the same; Fig. 4 is a top plan view of the insulating pin; Fig. 5 is a cross-sectional view on the line 5—5 of Fig. 1; and, Fig. 6 is a detail view of a modified form of insulating pin.

Referring more particularly to the drawings, the numeral 1 designates the main body portion of the insulating pin which is rectangular in side elevation having its four sides 2 formed so as to fit about the cross arm (not shown) of a wire supporting

means (not shown). The sides 2 of the main body portion 1 of the insulating pin are constructed of sheet metal which is practically semicircular in cross-section, having flanges 3 extending outwardly from their edges and longitudinally along the full length thereof. The semicircular portions 4 of the sides 2 are depressed as is shown at 5 in the drawings so as to permit the sides 2 to be bent so as to fit about the cross arms (not shown). The semicircular portions 4 form a reinforcement for the sides 2 and add materially to the strength of the same. The semicircular portion 6 of the side 7 of the body portion 1 is not depressed at the upper end of the side but extends upwardly beyond the upper side 8 of the body portion 1 and has a plurality of corrugations 9 formed upon its outer surface. The extreme upper end 10 of the semicircular portion 6 is depressed having a smaller radius than the portion upon which the corrugations 9 are formed. The upper side 8 of the body portion 1 has a semicircular portion 11 extending upwardly from its inner end and directly opposite the upstanding portion which has the corrugations 9 formed thereupon and is also provided with a plurality of exteriorly formed corrugations 12. The semicircular portion 11 extends upwardly at right angles from the longitudinal lines of the side 8 and parallel with the semicircular portion 6.

The two semicircular portions 6 and 11 are spaced apart, leaving a small opening 13 therebetween and are adapted to be seated within the screw-threaded recess formed in the interior of an ordinary type of glass insulator (not shown). The corrugations serve as a means for securely holding the insulator in place.

By the provision of the space 13 between the two semicircular portions 6 and 11 the latter will efficiently engage and support insulators of different sizes and which have different sized recesses formed therein in that the two sections 6 and 11 may be compressed and forced inwardly toward each other to fit smaller recesses. A washer 10' is also provided with corrugations so as to engage the corrugations 9 and 12 formed upon the two semicircular portions 6 and 11. This washer 10' securely clamps the insulator support upon the cross arm (not shown) and also tends to hold the

two semicircular portions in their proper positions as well as adding to the strength of the pin.

In Fig. 6 of the drawings a modified form 5 of insulator pin is shown, the same having the various sides 2' hingedly connected as is shown at 15.

In practical fields, certain minor features 10 of construction, combination and arrangement of parts may necessitate alterations to which the patentee is entitled, provided such alterations are comprehended within the scope of what is claimed.

What is claimed is:—

- 15 1. An insulator pin stamped from a single piece of semicircular tubing, the edges of the same being provided with longitudinally extending flanges and flattened portions at predetermined points to facilitate 20 the engagement of the same about a cross arm, upwardly extending spaced apart parallel arranged members for engagement with an insulator formed integral with the crossed arm engaging portion, and means 25 engaging the said upstanding portions whereby to clamp the semicircular tubing about a cross arm, and facilitate insertion into an insulator.
2. An insulator pin formed from a semi- 30 circular strip of metal depressed at prede-

termined points for engagement with a cross arm, lateral flanges formed on the edges of said strip and extending longitudinally thereof, upwardly extending parallel spaced arms for engagement with an insulator, said arms being provided with corrugations forming threads, and a ring embracing the said arms and provided with corrugations for engaging the corrugations on the up- 35 standing arms, whereby to facilitate the insertion of the same into an insulator and to clamp the device about a cross arm. 40

3. An insulator pin formed from a semi- 45 circular strip of metal depressed at prede- termined points to facilitate engagement with a cross arm, upwardly extending parallel spaced arms formed integral with said strip, said arms being semi-circular in cross section and corrugated, and a retaining ring 50 adapted for engagement with said corruga- tions when the semi-circular arms abut, said corrugations forming threads for receiving said retaining ring.

In testimony whereof I affix my signature in presence of two witnesses.

JASON BAKER.
